UNITED STATES PATENT OFFICE.

FRANK ANDERSON, OF PEEKSKILL, NEW YORK.

AUTOMATIC TELEGRAPHIC RECORDER.

SPECIFICATION forming part of Letters Patent No. 407,462, dated July 23, 1889.

Application filed May 7, 1889. Serial No. 309,862. (No model.)

To all whom it may concern:

Be it known that I, FRANK ANDERSON, a citizen of the United States, residing at Peekskill, in the county of Westchester and State 5 of New York, have made a new and useful Invention in Automatic Telegraphy, of which the following is a specification.

My invention relates particularly to improvements in automatic telegraphic receiving apparatus of the general type known as "chemical" or analogous automatic recording-receivers, and the object is to devise a page-message record in which the recorded characters of the Morse and analogous types 15 are arranged in concentric or parallel lines on a page of sensitized or equivalent receiving-paper, which shall avoid the annoying trouble incident to existing forms of page-records, wherein such characters are sometimes divided at the end of one line and the commencement of the subsequent line, thereby 20 puzzling the reader and preventing rapid reading. I accomplish this object by the arrangement of parts and construction of apparatus hereinafter described, and particularly pointed out in the claims which follow this specification.

In all automatic telegraphic page-receivers with which I am familiar wherein Morse and 30 analogous characters are either placed upon a sensitized record-page or by an ink-recorder said characters fill the entire page from edge to edge, and there arises a possibility that some of the characters or parts thereof may be unrecorded at the edges of the page. There also exists with such receivers a source of annoyance and delay to the reader of the recorded message in the fact that the combinations of recorded characters or symbols representing 35 a single letter are often divided at the ending of one line and the beginning of the line which follows, as I have already indicated in the statement of the object of my invention. My invention overcomes these annoyances, and a page-record is made having a 45 marginal line on each edge of the page similar to the marginal lines or edges of a book or printed page.

In order that my invention may be fully 50 understood, I will refer to the accompanying drawings, in which like letters of reference

represent like parts of the apparatus wherever used.

Figure 1 is a plan view illustrating diagrammatically the arrangement of parts of the 55 entire apparatus; and Fig. 2 is a side elevational view thereof, showing part in section.

N represents a rotary receiving - wheel adapted to be rotated by a handle I or by any source of power, said wheel being carried by 60 a shaft journaled in a frame. (Not shown.)

p p are recording-pens, and B B B are radial pen-carrying arms fixedly secured to electrical conducting-segments b b b, attached to and insulated from the wheel N and from each 65 other.

i i is a double - leaf conducting - spring adapted to bear upon the face of the conducting-segments b b b and connected by a wire w to the main line running to the distant 70 transmitting-station. (Not shown.)

P is a sheet of sensitized receiving-paper of the kind usually adopted in automatic telegraphy, said paper being fed forward over the metallic conducting-surface d by feed- 75 rolls e, f, and g.

w' is an earth-wire connecting the metal plate d to earth.

The apparatus described thus far constitutes the subject-matter of another application 80 for a patent filed by me in the United States Patent Office on the 9th day of February, 1889, No. 299,264, and I therefore make no claim to it here, the claims of the present application being directed to features which 85 I shall now describe, and also to such features in combination with the above - described mechanism.

S and S' are conducting contact - springs bearing normally upon the sensitized paper 90 P at points near the lower edge of the bearing conducting-plate d. These springs are connected in multiple arc by wires w² at t to the positive pole of a battery B A of sufficient current capacity to act upon the sensitized paper P, the other pole of said battery being connected by a wire w³ to the bearing plate or surface d.

The operation of the apparatus is as follows: The transmitter (not shown) having 100 been set in operation at the distant station, the wheel N is rotated at substantially the

same speed as the transmitter and the paper P is fed forward through the agency of feed-rolls e, f, and g, all as disclosed in my prior application above referred to. As the paper 5 advances the two marginal lines m and m' are recorded upon the edges through the agency of battery B A. As the successive segment b is brought beneath the two-part contact-spring i the current from the distant battery di-
10 vides between the two pens then on the sur-
face of the paper, and a duplicate record is
made so long as the insulated space between
these two segments is passing beneath said
two-part spring. This duplicate record, there-
15 fore, appears at the ending of the line where
the right-hand pen is passing out of circuit
and at the beginning of the next line where
the second or left-hand pen is passing in.
Now, the space between the two contact-
20 springs S and S' bears a fixed relation to the
areas of the successive segments, so that all of
the record made to the left and right of the
lines m' and m is in duplicate. In reading
the record therefrom the operator has simply
25 to read either all of the record to the left of
line m or all to the right of line m', or all be-
tween lines m and m', and should he be in
doubt about any character at the end of a
line he need only look at the characters out-
30 side the lines m and m' to ascertain if the
letter is complete at the end of the line or
has been continued on the next line below.
Inasmuch as the record is duplicated at the
opposite edges of the page when any two
35 pens are on the paper, and as the distance
between the two lines m and m' equals the
angular distance between the pens, all that
portion of the record made to the right and
left of these two lines is repeated, and by glanc-
40 ing at the record thus made on the suc-
cessive lines it will be at once apparent whether
a letter is complete at the right-hand end of
the line or is partially recorded on the next
succeeding line. In other words, if a dash oc-
45 curs directly on the right-hand line m', as the
pen goes out of circuit, a glance at the left-hand
end of the next succeeding recorded line will
disclose to the reader if this dash is the end
of that letter or is followed by an independ-
50 ent letter.

It will be understood that the record must be read as commenced, either between the lines m and m' or to the left or right, as indicated, and after one becomes accustomed to the system it is found possible to read very rapidly.

I do not limit myself to the specific means shown for thus rendering possible the rapid and intelligible reading of page-records, as it 60 is obvious that many modified forms might be

submitted by which the repeated characters are made.

I may and sometimes do use sensitized pa-
per already prepared with the lines m and
m' having the required spacing-distance. 65 These lines may be previously ruled upon the
paper by inking-pens or in any preferred
manner.

Having thus described my invention, what I
claim, and desire to secure by Letters Patent 70
of the United States, is—

1. In an automatic telegraphic receiver of
the page type, a message-blank having mar-
ginal lines, in combination with a receiving-
recorder having a series of pens connected to 75
contacting surfaces, insulated from each other,
and electrically connected by a two-point
contact-spring to the distant transmitter, the
contacting surfaces having a fixed relation to
the distance between the two marginal lines, 80
whereby the characters near the ends of the
successive lines are repeated, substantially
as described.

2. An automatic telegraphic record con-
sisting of a series of concentrically-recorded 85
lines of characters upon a sheet of sensitized
paper or equivalent material, said record hav-
ing a definite portion of the characters re-
peated at the ending and beginning of suc-
cessive lines, substantially as described. 90

3. An automatic telegraphic record con-
sisting of a series of concentrically-recorded
lines of characters upon a sheet of sensitized
paper or equivalent material, said record-pa-
per having two marginal lines as indexes, out- 95
side of which all the characters or portions
thereof representing telegraphic symbols are
repeated, substantially as described.

4. The combination of two or more rotary
receiving-pens with apparatus for producing 100
marginal lines upon a sensitized page-record,
consisting of two electrical contact pens or
springs connected to one pole of an electrical
generator, in combination with a sensitized
sheet of paper and a contacting surface con- 105
nected to the other pole of said electrical
generator, substantially as described.

5. The combination of two or more rotary
receiving-pens with means for making mar-
ginal lines on a page-record, consisting of 110
two contact-pens, in combination with a sen-
sitized sheet of paper, a conducting support-
ing-surface, and an electrical generator con-
nected to said pens and the conducting-sur-
face, substantially as described.

FRANK ANDERSON.
